(57) **CLAIM**

The ornamental design for a projection lamp, as shown and described.

DESCRIPTION

FIG. 1 is a perspective view of a projection lamp showing my new design;

FIG. 2 is an exploded view thereof;

FIG. 3 is a perspective view of a projection lamp main body of the projection lamp shown separately for illustration;

FIG. 4 is another perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof;

FIG. 11 is a perspective view of a projection lamp holder of the projection lamp shown separately for ease of illustration;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof; and,

FIG. 19 is an exploded view thereof.

The broken lines in the drawings depict portions of the projection lamp that form no part of the claimed design.

1 Claim, 19 Drawing Sheets
